REFRIGERATING APPARATUS

Robert R. Candor, Oakwood, Ohio, assignor to
General Motors Corporation, Dayton, Ohio, a
corporation of Delaware

Application December 30, 1940, Serial No. 372,226

6 Claims. (Cl. 62—6)

This invention relates to refrigeration and more particularly to a refrigerating system in which heat rejected by the condenser is used for reheating the air.

One object of this invention is to provide a system in which air to be conditioned is first circulated over an evaporator and is thereafter circulated over a reheat coil through which water from an evaporative condenser may be circulated in accordance with reheat requirements.

A further object of this invention is to provide means for controlling the temperature of the water in an evaporative condenser.

A further object of this invention is to provide an improved control arrangement for use in an air conditioning system.

Still another object of this invention is to provide an improved conditioning system which is especially well suited for supplying conditioned air to a plurality of rooms.

Further objects and advantages of the present invention will be apparent from the following description, reference being had to the accompanying drawings, wherein a preferred form of the present invention is clearly shown.

In the drawings:

Fig. 1 is a diagrammatic view partly in section showing one embodiment of my invention;

Fig. 2 shows the control circuit suitable for use in a system of the type disclosed in Fig. 1;

Fig. 3 is a diagrammatic view partly in section showing a modified form of a refrigerating system embodying my invention.

In the preferred embodiment of my invention as shown in Fig. 1, an air conditioning cabinet 10 is provided which is adapted to be mounted directly within the enclosure to be conditioned or arranged in a duct system for supplying conditioned air to the enclosure. Reference numeral 12 designates a casing within which is mounted an evaporative type of condenser 14. Compressed refrigerant is supplied to the condenser 14 by means of a compressor 16 which may be mounted either in the cabinet 10 as shown, or in the cabinet 12. The refrigerant condensed in the condenser 14 collects in the receiver 18 from whence liquid refrigerant is supplied to the evaporator 20 mounted adjacent the air inlet 22 of the main air conditioning cabinet 10. The flow of refrigerant to the evaporator 20 may be controlled by any conventional control means such as the thermostatic expansion valve 24 which may be of any conventional construction. Air to be conditioned is circulated over

the coil 20 by means of a blower 26 arranged within the cabinet 10. The blower discharges the conditioned air through the outlet 30, which for purposes of illustration has been shown as located in the top wall of the casing 10. A motor 32 drives the blower unit 26. The compressor 16 is driven by means of a separate motor 34.

A reheat coil 40 has been provided adjacent the outlet 30 for reheating the conditioned air whenever reheating is required. Cooling water is sprayed over the condenser 14 by means of the spray unit 42 at all times when refrigeration is required. A pump 44, driven by an electric motor 46, or any other available power source, withdraws water from the main water sump 48 and discharges the water through the line 50, leading to the three-way valve 52. In the one position of the three-way valve 52, the water is supplied through the pipe 50 and is discharged directly into the line 54 leading to the spray unit 42. In the other position of the valve 52, the water supplied to the pipe 52, is caused to flow through the line 56 leading to the reheat coil 40. The water leaving the reheat coil 40 flows through the line 58 which connects with the line 54 leading to the spray device 42. Condenser cooling air is circulated in countercurrent relationship to the water spray of the condenser coil 14 by means of the dual blowers 60. The condenser cooling air enters the cabinet 12 through the inlet 62 and is discharged therefrom through the outlets 64. The amount of air circulated through the cabinet 12 is controlled by the damper 66, arranged adjacent the air inlet 62. The damper 66 is in turn controlled by the damper operating motor 68. A certain amount of make-up water will be required from time to time due to the evaporation of a portion of the spray water. Make-up water is supplied through the water supply pipe 70. The amount of water supplied through the pipe 70 is controlled by a conventional float control mechanism 72. Reference numeral 73 designates a condensate drain line through which the moisture removed by the evaporator 20 is conveyed to the water sump 48. The blowers 60 are operated by means of an electric motor 74 arranged as shown in Fig. 1.

Referring now to Fig. 2, in which I have shown the control circuit for the system shown in Fig. 1, reference characters 77 and 79 designate the electrical power lines and reference character 80 designates a thermostat which is adapted to respond to the dry bulb temperature of the air within the conditioned space. Whenever the temperature of the air within the conditioned

space indicates that conditioning is required, the thermostat 80 will close the circuit leading to the compressor motor 34, the water pump 46 and the blower motor 74 so as to initiate operation of the refrigerating system so as to cool the air. The reheat mechanism may be controlled either by the thermostat 81 or the humidostat 82. Manual switches 83 and 85 are provided for connecting one or the other of the reheat controls into the circuit as shown. In the event that the humidostat 82 is in control and the relative humidity within the conditioned space is higher than desired, the humidostat 82 will close the circuit through a solenoid coil 84. Energization of the solenoid 84 causes closing of the switches 86 and 88. Switch 86 is arranged in parallel with the thermostatic switch 80 whenever the manual switch 92 is closed, whereby closing the switch 86 starts up the cooling apparatus if the thermostat 80 has not already started up the cooling apparatus. Closing of the switch 88 causes energization of the damper operating motor 68 and the three-way solenoid valve 52. Energization of the damper operating motor 68 causes damper 66 to move toward its closed position. Energization of the three-way solenoid valve 52 causes the valve to direct the flow of water from the pipe 50 into the pipe 56 leading to the reheat coil 40.

By virtue of the above described arrangement, whenever the switch 85 is closed and the relative humidity in the conditioned space exceeds a predetermined value, for which the humidostat 82 is set, cooling and thereafter reheating of the air will take place. Furthermore, closing of the damper 66 causes the temperature of the condenser water to increase whereby a greater amount of heat is made available for reheating the air than would be available if the usual amount of air were permitted to flow in counter-current flow relationship to the water sprayed over the condenser. Upon opening of the circuit leading to the damper motor 68 and the solenoid valve 52, the damper 66 returns to its fully opened position and the valve 52 returns to that position in which it directs all of the water flowing through the pipe 50 directly into the line 54 leading to the spraying device 42. A manually operated switch 90 is provided for turning on and off the entire system.

While I have disclosed "on" and "off" type of controls for the valve 52 and the damper 66, it is obvious that modulating controls could be used if desired. By closing the switch 83 and opening switches 85 and 92, the dry bulb thermostat 81 is substituted for the humidostat 82 in the reheat control circuit. The thermostat 81 is arranged to open the circuit to the solenoid 84, whenever the dry bulb temperature in the space indicates that the temperature in the conditioned space is already too high to warrant reheating and is adapted to close the circuit to the solenoid 84 as the indoor temperature approaches the temperature at which the thermostat 80 would shut off the refrigerating system. By virtue of this arrangement reheating takes place only at such times when the refrigerating apparatus has excess capacity and then only if the thermostat 80 calls for cooling.

By virtue of the dual control arrangement, the reheat apparatus may, for example, be placed under the control of the humidostat 82 at night and under the control of the thermostat 81 during the day. In this manner the system may be used primarily as a drying system at night and

as a comfort cooling system during the day. The manually controlled switches 83, 85 and 92 could be operated by means of any conventional "day" "night" control clock if desired.

In Fig. 3, I have shown a modified arrangement for use in conditioning a plurality of enclosures. In this modification the refrigerant evaporator 120 and the reheat coil 130 have been arranged side by side adjacent the outlet of the conditioning cabinet 110. In this modification reference numeral 102 has been used to designate one of a plurality of rooms adapted to be supplied with conditioned air. The blower 126 withdraws air to be conditioned from the rooms through the return air duct 122 and discharges the conditioned air through a pair of ducts 103 and 104 which are provided with a plurality of outlets such as 112 and 114 shown for the room 102. Inasmuch as all of the air flowing over the refrigerant evaporator 120 discharges into the duct 103 and all of the air flowing over the reheat coil 130 discharges into the duct 104, it is apparent that either cooled air, heated air or a mixture of both may be supplied to each enclosure to be conditioned.

By properly proportioning the amount of cool air and heated air supplied to each enclosure, the temperature of the air in each enclosure may be closely regulated. As shown in connection with room 102, a pair of dampers 105 and 106 are provided for controlling the amount of heated air and cooled air introduced into each enclosure. The damper 105 controls the amount of heated air introduced whereas the damper 106 controls the amount of cooled air introduced. These dampers are operated by means of a common damper operating motor 107 which is under the control of the room thermostat 108, the arrangement being such that as the one damper opens, the other damper closes a corresponding amount so that the total volume of air introduced into the enclosure remains substantially constant. In the modification shown in Fig. 3, the evaporative condenser unit is similar to the evaporative condenser unit disclosed in Fig. 1. The same reference numerals have been used to designate corresponding similar parts in Figs. 1 and 3.

In the modification shown in Fig. 3, the three-way valve 52 and the damper 66 may be permitted to remain in the position in which maximum heating is provided by the heating coil 130 at all times, or they may be operated in the same manner in which these elements are operated in the modification shown in Fig. 1 in which case the control instruments 80, 81 and 82 would all be located in the one room which most closely represented the condition in each of the other rooms. The valve 52 and damper 66 determine where the heat picked up by the evaporator 120 is to be discharged. Thus the heat may be discharged into the outside air circulated by the fans 60 or it may be discharged into the air flowing into the duct 104. There will be times when the climatic conditions or the type of occupancy of the enclosures is such that the amount of heat which must be added to the air for some of the enclosures will substantially equal the amount of heat which must be removed from the air for other of the enclosures, in which case the refrigerating system will be required to operate so as to assist in maintaining the proper conditions in each of the enclosures.

Thus the controls shown in Fig. 2 may be used in conjunction with the apparatus and controls shown in Fig. 3, or as explained herein-

above, the three-way valve 52 and the damper 66 may be permitted to remain in the position in which maximum heating is provided by the heating coil 130 at all times. The selection of controls used and the settings of these controls would be governed by many factors including climatic conditions, occupancy of the conditioned space and the results desired. For purposes of illustration, the thermostat 108 may be so adjusted as to hold the damper 106 wide open above temperatures of 90° and fully closed at temperatures below 70°. The thermostat 88 may be set so as to energize the apparatus at temperatures above 75°, and a thermostat 81 may be placed in control of the elements 52 and 68 so as to cause reheating at temperatures below 82°. The above values are given solely for purposes of illustration.

While the form of embodiment of the invention as herein disclosed, constitutes a preferred form, it is to be understood that other forms might be adopted, all coming within the scope of the claims which follow.

What is claimed is as follows:

1. In combination an evaporator, means for circulating air to be conditioned in thermal exchange with said evaporator, means for reheating said air, refrigerant liquefying means for supplying liquid refrigerant to said evaporator, said refrigerant liquefying means comprising a compressor and a condenser, means for spraying cooling water over said condenser, means for circulating air in thermal exchange with said condenser and said spray water, means for circulating a portion of said water through said reheat means, and humidity responsive means for controlling the flow of air over said condenser.

2. In combination an evaporator, means for circulating air to be conditioned in thermal exchange with said evaporator, means for reheating said air, refrigerant liquefying means for supplying liquid refrigerant to said evaporator, said refrigerant liquefying means comprising a compressor and a condenser, means for spraying cooling water over said condenser, means for circulating air in thermal exchange with said condenser and said spray water, means for circulating a portion of said water through said reheat means, and means responsive to the moisture content of the conditioned air controlling said reheat means.

3. In combination an evaporator, means for circulating air to be conditioned in thermal exchange with said evaporator, means for reheat-

ing said air, refrigerant liquefying means for supplying liquid refrigerant to said evaporator, said refrigerant liquefying means comprising a compressor and a condenser, means for spraying cooling water over said condenser, means for circulating air in thermal exchange with said condenser and said spray water, means for circulating a portion of said water through said reheat means, humidity responsive means for controlling the flow of air over said condenser, and the flow of water to said reheat means.

4. Apparatus for conditioning air including an evaporator, compressor and an evaporative surface condenser comprising a complete refrigerating system, said evaporator cooling the air to a temperature below that desired for the conditioned air, said evaporative surface condenser including means for spraying water over the condenser, a reheat for reheating the air, said reheat forming a part of an auxiliary heat transfer system using the condenser spray water for restoring to the cooled air a portion of the heat rejected by said condenser, and means for controlling the rate of evaporation of said spray water.

5. Air conditioning apparatus for an enclosure comprising in combination, means for removing heat from air for said enclosure including an evaporator, heat exchange means for returning a portion of said heat to air for said enclosure, refrigerant liquefying means for supplying liquid refrigerant to said evaporator, said refrigerant liquefying means comprising a compressor and a condenser, means for spraying cooling water over said condenser, means for circulating air in thermal exchange with said condenser and said spray water, means for flowing a portion of said water through said heat exchange means, and means for controlling the amount of heat returned to the air by said heat exchange means.

6. Apparatus for conditioning air including an evaporator, compressor and an evaporative surface condenser comprising a complete refrigerating system, said evaporative surface condenser including means for spraying water over the condenser, a heater for heating air, means for flowing air to be conditioned over said evaporator and said heater in parallel, said heater forming a part of an auxiliary heat transfer system using the condenser spray water for restoring to the air a portion of the heat rejected by said condenser, and means for controlling the amount of heat restored to the air by said heater.

ROBERT R. CANDOR.
